CLOSURE CAP OR SIMILAR ARTICLE

George J. Foss and Daniel D. Acton, Lancaster, Ohio,
assignors to Anchor Hocking Glass Corporation, Lan-
caster, Ohio, a corporation of Delaware

Filed Dec. 19, 1960, Ser. No. 63,256

Term of patent 14 years

(Cl. D58—26)

FIG. 1 is a perspective view of a closure cap, showing our new design;

FIG. 2 is a top plan view thereof;

FIG. 3 is a bottom plan view thereof;

FIG. 4 is a side elevational view thereof, and

FIG. 5 is an enlarged sectional view taken along line 5—5 of FIG. 2.

The characteristic features of the invention reside in a closure cap or similar article comprising a substantially cylindrical skirt portion with a plurality of equally spaced indentations therein, each of the indentations being of

substantially the same width and comprising a lower inwardly curved portion and an upper substantially straight portion.

We claim:

The ornamental design for a closure cap or similar article, substantially as shown and described.
